UNITED STATES PATENT OFFICE.

JOHN A. BELL AND SYDNEY W. REYNOLDS, OF LATHROP, CALIFORNIA.

WINDMILL.

No. 874,382.

Specification of Letters Patent.

Patented Dec. 24, 1907.

Application filed November 7, 1906. Serial No. 342,342.

To all whom it may concern:

Be it known that we, JOHN A. BELL and SYDNEY W. REYNOLDS, citizens of the United States, residing at Lathrop, county of San Joaquin, State of California, have invented certain new and useful Improvements in Windmills; and we do declare the following to be a full, clear, and exact description of the same, such as will enable others skilled in the art to which it appertains to make and use the same, reference being had to the accompanying drawings and the characters of reference marked thereon, which form a part of this specification.

This invention relates to improvements in wind mills, our object being to produce a simple and effective wind mill, in which all the power generated by the wheel of the mill will be utilized without any lost motion or any unnecessary gear; also one which may be easily handled; and lastly one provided with a simple automatic lubricator. These objects we accomplish by means of an endless gear suitably connected to a driving shaft, and means connected with said endless gear for operating the lifting rod; also by such other and further constructions as will appear by a perusal of the following specifications and claims.

In the drawings similar characters of reference indicate corresponding parts in the several views.

Figure 1 is a side elevation of our improved device with a portion of the casing broken away. Fig. 2 is a section on Y Y of Fig. 1. Fig. 3 is a section on line X X of Fig. 1 looking to the right. Fig. 4 is a similar section looking to the left. Fig. 5 is a section taken on a line Z Z of Fig. 4.

1 designates the frame beams of the mill which uphold a turn table consisting of base members 2 which are formed with two tubular members 3 and 4, one within the other, leaving a space 5 therebetween, in which space 5 a tubular support 6 is arranged, said support 6 upholding the gear box 7 of the mill. This gear box 7 is formed of a cast box divided into two oval chambers 8, the upper one of said chambers 8 opening into a chamber 9, which chamber 9 is connected with the tubular support 6 by means of a semi-tubular member 10. In said chamber 9 is arranged the lifting rod 11 extending through the member 10 and 6 and provided with a slotted cross head 12. 13 is a small pinion wheel secured on the shaft of the mill within

the box 7 at the center thereof, and intermeshing with an endless rack gear 14 secured to a bar 15, which bar 15 is pivotally secured to rollers 16 which bear against the sides of the chambers 8. At the upper end of the bar 15 opposite to the roller 16 is a small roller 17 which extends into the slot in the cross head 12, for the purpose as will appear. Bolted plates 8^a provide openings into the chambers 8.

In practice the rotation of the wheel of the mill rotates the pinion wheel 13 which, intermeshing with the gear 14, drives the bar 15 and rollers 16 around in the chambers 8, thus giving the same an up and down stroke, and since the roller 17 operates in the slot of the cross head 12, this gives the lifting rod 11 an up and down reciprocating movement as is required.

Another valuable feature of our invention is that it may be automatically lubricated as follows:—The lower one of the chambers 8 may be filled with lubricant. As the bar 15 and its parts make their movement they pass through the oil and carry a sufficient amount upward to lubricate all the gearing. To lubricate the shaft of the mill we run a pipe 24 from the lower end of the upper chamber 8 to the shaft box, and a pipe 25 leads from the outer end of the shaft box to the lower chamber 8 for the purpose of returning the surplus lubricant. The lower end of the lower chamber 8 is formed of a movable member 26, the position of which is regulated by means of set screws 27 for the purpose of taking up any possible wear.

18 indicates the usual frame for the vane 18^a, this frame being carried by brackets 20, 20^a carried by the casing 7 and the casing of chamber 9 respectively. This frame is shiftable to pull the wheel out of the wind by means of a cable 21 attached at one end to the frame and then passed over pulley 22 carried by the casing of chamber 9, over a pulley 23 within upper chamber 8 and down through members 10 and 6 to the tail lever (not shown) at the foot of the mill. As the particular manner of shifting this frame is not a part of the improvement embodied in the casing 7, further detailed description is believed to be unnecessary as the specific construction of these parts is not dependent upon the construction of the mechanism herein claimed.

Thus it will be seen we have produced a wind mill in which the power of the wheel is

all utilized, the endless rack gear 14 preventing any loss of power; also a mill which is easily constructed and handled; and lastly one which may be automatically lubricated 5 by a simple and inexpensive means.

This description embodies the present and preferred construction of the device. However, in practice such construction may be changed slightly from its present form, but 10 such changes will not of course depart from the spirit of the invention.

Having thus described our invention, what we claim as new and useful, and desire to secure by Letters Patent is:—

15 1. In a wind mill, a casing having spaced interior guide chambers, a drive shaft journaled in said casing and carrying a gear wheel operating between said guide chambers, a frame having rollers for operating in 20 said guide chambers and with a laterally extending operating roller, an endless gear rack carried by said frame and operatively engaged by said gear, and an operating rod having a transverse slot and adapted to be 25 engaged by said lateral bearing roller.

2. In a device of the class described, a casing having elongated interior chambers spaced apart and with rounded ends and with a lateral chamber communicating with 30 one of said elongated chambers, a drive shaft journaled in said casing between said chambers and carrying a gear wheel, a frame hav-

ing rollers for operating in said guide chambers and with a lateral bearing roller extending into said laterally communicating chamber, an endless gear rack carried by said frame and operatively engaged by said gear, and an operating rod movably disposed in 35 said lateral chamber and provided with a transverse slot adapted to be engaged by 40 said lateral bearing roller.

3. In a wind mill, a casing having spaced elongated guide chambers having rounded ends with the outer end of one of said chambers adjustable longitudinally thereof and 45 with a lateral chamber communicating with the other of said elongated chambers, a shaft provided with a gear operating between said elongated chambers, a frame having rollers operating in said guide chambers and with a 50 bearing roller extending into said lateral chamber, an endless gear rack carried by said frame and operatively engaged by said gear, and an operating rod movable in said lateral chamber and having a transverse slot adapted 55 to be engaged by said lateral bearing roller.

In testimony whereof we affix our signatures in presence of two witnesses.

JOHN A. BELL.
SYDNEY W. REYNOLDS.
